STARTING APPARATUS FOR INTERNAL COMBUSTION ENGINES

Charles S. Brown, Syracuse, N. Y.

Application January 10, 1934, Serial No. 706,093

1 Claim. (Cl. 123—180)

This invention relates to starting apparatus for internal combustion engines, particularly multi-cylinder four cycle engines, and has for its object starting apparatus by which the engine is started by apparatus which forms, compresses and builds up to ignition point compression and fires a charge of explosive mixture in the cylinder or cylinders in which both of the regular intake and exhaust valves are closed and in which the piston is stopped somewhere on its out or working stroke, regardless of what position the piston has assumed, whether at the beginning, intermediate or toward the end of its working stroke. The engine is kept running in this manner, until it becomes self-operative through the regular operation of the charge coming in through the regular intake valves.

The invention further has for its object a method of starting a multi-cylinder internal combustion engine by forcing a charge into, and compressing it in, the cylinder or cylinders in which the regular exhaust and intake valves are closed, up to the ignition point compression of the charge regardless of the position of the piston in its cylinder on its working stroke and firing the charge.

Other objects will appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a diagrammatic view of a six cylinder internal combustion engine embodying the invention, the engine being shown in plan view partly in section and certain parts being omitted.

Figure 2 is an enlarged vertical, sectional view through one of the cylinders and the additional valve mechanism forming part of this invention, illustrating one adaptation to internal combustion engines.

Figure 3 is a fragmentary view illustrating a slightly different arrangement of the compressor relative to the carburetor.

This starting mechanism for internal combustion engines comprises means for forming and compressing an explosive mixture in the cylinder or cylinders of the engine in which both the intake and exhaust valves are closed and the piston of which has stopped somewhere in its working stroke when the engine stopped, and means for firing the charge when it reaches an ignition

point compression in any position of the piston in the working stroke. The method of starting multi-cylinder internal combustion engines consists in forming and forcing an explosive mixture into the cylinder or cylinders in which both the intake and exhaust valves are closed when the engine stopped, building up the compression in that cylinder or cylinders to the firing point compression and firing the charge, regardless of the position in the working stroke occupied by the piston in that cylinder or cylinders.

As is well known, an explosive mixture must be compressed to a predetermined compression before a spark will ignite it, and in the interest of brevity, the term "firing point compression" or "ignition point compression" is used to identify the amount of compression required before the explosive mixture will ignite.

In the ordinary operation of internal combustion engines, this compression point is reached when the piston is at or near the position assumed by the piston when at the end of its "in" compression stroke. Normally a partially compressed charge or a charge taken in the regular way will not ignite regularly, at least not readily enough to count on it as a starting means.

By this invention, when the engine is stopped, the compression of an explosive mixture is built up in the cylinder or cylinders in which the pistons are anywhere below top dead center on their "out" working strokes, when the engine is stopped, and then firing the compressed charge and hence starting the engine. In that cylinder or cylinders obviously, both the regular intake and exhaust valves will be closed so that the cylinder or cylinders receive a compressed charge. A cylinder in which the piston is one-half way down when the engine is stopped will require a larger compressed charge than the cylinder where the piston stops one-quarter of the way down. In any case, the charge will have to be compressed to an ignition point, regardless of whether the piston is one-quarter, one-half or nine-tenths of the way down in the cylinder.

The invention is here illustrated as embodied in a six cylinder engine, although it may be embodied in a four cylinder engine, but as the four cylinder engine is liable to stop on a dead center, it is preferable to use an engine of more than four cylinders.

The reference numeral 1 designates an internal combustion engine, here shown as having six cylinders. The engine has the usual pistons, crank shaft, etc. Each cylinder has the usual intake and exhaust valves 2, 3, operated by cam 55

shaft 4, and intake and exhaust manifold and also the usual carburetor and ignition system including a spark plug 5 for each cylinder. After being started, the engine operates in the same manner as any four cycle engine, and this invention relates to the starting without the use of an electric motor for rotating the engine crank shaft but by the forming and compressing and igniting of a charge in the cylinder or cylinders in which both valves are closed when the engine stops and the piston is on the working stroke.

In the illustrated embodiment of the invention, the engine is provided with an additional intake valve, here illustrated as a rotary valve 11 suitably mounted in a casing 12 provided along one side of the cylinder block, the casing having a port 13 opening into a passage 14 which opens into the cylinder or compression chamber 15 formed in the cylinder head 16 in any well known manner. The rotary valve 11 is formed hollow and with outlet ports 17, one for each cylinder, the ports 17 being designed to come into and out of registry with the ports 13. The rotary valve 11 is actuated to time and distribute any charge that may be forced therethrough to the engine cylinder, and as here shown, it is actuated and timed from the cam shaft 4, as through a chain 18 running over gears 19 and 20 on the cam shaft 4 and the rotary valve 11 or a shaft extension 21 thereof. The rotary valve is mounted in suitable anti-friction bearings 22 in the housing 12.

The means for forming and compressing the charge in the cylinder or cylinders in which the valves are closed when the engine is stopped, comprises an air compressor 23 of any suitable construction and an electric motor 24 connected to the compressor 23 to actuate the same, an outlet conduit 25 leading from the compressor through the carburetor and communicating at 26 with one end of the hollow rotary valve 11. The section of the conduit leading from the compressor communicates with the air intake of the carburetor and the other section of the conduit, that is, the section leading to the rotary valve, communicates with the vapor outlet of the carburetor.

The electric motor is controlled by a switch 34—42 operable at the will of the operator.

The charge forced into the cylinder or cylinders by the compressor is fired by a spark plug or plugs 28 in an ignition system controlled by the switch which controls the electric motor and hence is synchronized with the charge forming means.

The starting ignition system includes a circuit having a vibrator coil therein of the type in which a spark is produced during each vibration and the output of the vibrator coil is distributed to the additional spark plugs 28 for the proper cylinders through a suitable distributor 29.

The reference numeral 30 designates the vibrator coil which may be of any suitable and well known construction.

The reference numeral 31 designates a battery or source of current, one side of which is grounded at 32 and the other side of which is connected by a conductor 33 to a terminal 34. The primary coil of the vibrator is connected to the battery through a conductor 35 having a terminal 36 at one end and connected at its other end to the primary coil, the primary coil being grounded at 37. The secondary coil is connected

by a wire 38 to the distributor 29 and the contacts of the distributor 29, in this instance being six in number, are connected to spark plugs 28 of the various cylinders through conductors as 39. The distributor 29 may be of any suitable construction, except that the contacts of the distributor are comparatively wide so that the spark plug connected to any contact with which the distributor arm is engaged will spark continuously, when the piston is at any point on its working stroke in the cylinder. Thus, when this starting ignition circuit is closed, the spark will continue and when the compressor has built up the compression of the explosive mixture to the ignition point, the spark plug 28 will fire and a flame wave will be propagated through the compressed charge and start the engine regardless of the point or position of the piston. The electric motor 24 is grounded at 40 and has its starting circuit connected through a wire 41 having a suitable switch 42 therein, this switch being normally open and when closed engaging the contacts 34 and 36 so that when it closes the motor circuit, it also closes the ignition circuit through the vibrator 30 or the primary coil 25 thereof.

Means are provided to relieve the charge forming means or carburetor from the force of the explosion in the cylinder, and this means is preferably located so as to also relieve the valve mechanism including the rotary valve 11 from the force of the explosion and, as here illustrated, comprises a check valve, as the check valve 50, located in each passage 14 between the rotary valve and the engine cylinder compression chamber, the valve 50 being opened by the pressure of the charge created by the air compressor 23 against the action of a light returning spring 51.

A check valve 52 may be located in the conduit 40 to protect the carburetor or compressor against backfiring and when the check valve 52 is employed, the valve 50 may or may not be omitted. In order to further protect the carburetor against backfiring, the carburetor 27a may be connected 45 as shown in Figure 3 to the conduit 25a, communicating with the air intake side of the compressor 23a so that the air is drawn by suction through the carburetor instead of being forced through, as in Figure 1.

The engine here shown is formed with a T-shaped compression chamber with the regular intake and exhaust valves 2, 3 seating at one side of the cylinder in the bottom wall of the compression chamber and the check valve 50 seating at the other side of the cylinder also on the bottom wall of the compression chamber.

In operation, when the engine stops at least one of the cylinders of a six cylinder engine will stop with its piston somewhere on its working stroke. Also, when the engine stops, one or more of the ports 17 of the rotary valve 11 will be in alignment with the port 13 of the cylinder or cylinders in which both the intake and exhaust valves 2, 3, respectively, are closed and the piston is on its working stroke. To again start the engine, the switch 42 is closed, thus causing the motor 24 to actuate the compressor 23 and also to close the circuit through the vibrator coil 30. During the operation of the compressor 23, air is forced 70 through the conduit 25 and the carburetor 27 thus forming an explosive mixture and forcing the said mixture through the rotary valve 11 and out through the port or ports 17, which are in communication with the port or ports 13 of the 75

cylinder or cylinders in which the regular intake and exhaust valves are closed. When the pressure has been built up in the cylinder, by the action of the compressor 23, to the point of ignition by compression, the spark at the spark plug 28 will propagate and ignite the charge causing the engine to start. The operator keeps the switch 42 closed until the engine runs regularly, that is, by drawing in its charge through the regular intake valve 2.

By this starting mechanism, an engine can be started under partial load, so that the driving clutch would not have to be released during starting, as is now necessary in many internal combustion engines. Under light or even normal loads, this engine could be made to operate with the combined use of the starting switch and controlling throttle valve with much the same flexibility as a steam engine is controlled by its throttle.

What I claim is:

The combination with a multi-cylinder internal combustion engine having the usual cylinders, pistons, crank-shaft and the regular intake and exhaust valves and valve mechanism, of mechanism including additional intake valve means,

connections between the crank-shaft of the engine and the additional valve means to actuate and time the same, said valve means being operable to communicate with any one of the cylinders in which both regular valves are closed and the piston therein anywhere on its working stroke, means for forming and compressing an ignitable charge through the additional valve means into the cylinder in which both valves are closed and the piston somewhere on its working stroke, and building up the compression to an ignition point, ignition means synchronized with the additional valve means for firing the charge in the cylinder in which the regular valves are closed when the ignition point compression is reached, an electric motor for actuating the compressing means, and a switch operable to close the motor circuit and the circuit of the ignition means, all whereby upon the closing of the electric circuit through the motor, an ignitable charge is forced through the additional valve means into any one of the cylinders in which both the regular valves are closed and the charge compressed and ignited.
